CASING FOR A TEXTILE YARN BEAMING UNIT

John Cocker III, Gastonia, N.C., assignor to Cocker
Machine and Foundry Company, Gastonia, N.C., a
corporation of North Carolina

Application September 11, 1958, Serial No. 52,609

Term of patent 14 years

(Cl. D55—1)

FIG. 1 —

FIG. 2 —

FIG. 3

FIG. 4

Fig. 1 is a perspective view of a casing for a textile yarn beaming unit embodying my new design;

Fig. 2 is a view in side elevation thereof;

Fig. 3 is a view in front elevation thereof; and

Fig. 4 is a plan view thereof.

I claim:

The ornamental design for a casing for a textile yarn beaming unit, as shown.
